(57) **CLAIM**

The ornamental design for a charging station for electric vehicles as shown and described.

DESCRIPTION

FIG. 1 is a front, left and top perspective view of a charging station for electric vehicles showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged partial view of a circled portion 9 of FIG. 1; and,

FIG. 10 is an enlarged partial view of a circled portion 10 of FIG. 2.

In the drawings, the diagonal shading lines in FIGS. 1-4 and 9-10 show a reflective surface and are not surface ornate-
tations.

In the drawings, the dot-dot broken lines depict portions of the charging station for electric vehicles that form no part of the claimed design. The dot-dash broken lines depict the boundaries of the enlarged partial views, and the lead lines; and form no part of the claimed design.
